SAFETY DEVICE FOR ROOFERS

John R. Lancaster and Johnathan B. Ward,
Goldsboro, N. C.

Application March 30, 1932, Serial No. 602,078

3 Claims. (Cl. 304—22)

The object of this invention is to provide an anchoring device whereby workmen employed upon an inclined roof may perform their duties safely. The invention seeks to provide a device especially adapted for use upon metallic roofs having upstanding seams or flanges extending over the same and which is adapted to firmly clamp the seams or flanges and thereby furnish a firm support for a ladder, a cable, or other device provided for the support of the workmen. The invention is illustrated in the accompanying drawing and will be hereinafter fully described and particularly defined.

In the accompanying drawing, Figure 1 is a plan view of a portion of a hip roof showing the improved anchoring device in position thereon and a ladder held by the anchoring device.

Fig. 2 is an enlarged plan view of the device removed from the roof.

Fig. 3 is an edge view of the anchor.

Fig. 4 is a section on the line 4—4 of Fig. 2.

The reference numeral 1 indicates a portion of a tin roof and the numeral 2 indicates an upstanding seam or flange which extends over the roof and is formed in the process of laying the metal. In carrying out the present invention, there is provided a base bar 3 which is preferably of some substantial weight and is adapted to lie flat upon the roof against one side of the seam 2 or flange, as shown most clearly in Fig. 4. Upon this base bar, adjacent the ends thereof, are secured blocks or arms 4 which project laterally from the bar and are intended to extend over the flange or seam, as shown in Figs. 2 and 4, each arm being provided in its underside with a notch 5 whereby it may fit closely to the seam or flange. Pivoted to the ends of the respective arms 4 are levers 6 which extend in the same direction from their respective pivots, as shown in Fig. 2, and have the ends of their shorter arms provided with enlargements or flanges 7 of arcuate form whereby they are adapted to rock upon the side of the flange or seam 2 and bear against the same, as will be understood upon reference to Figs. 2 and 4.

The ends of the longer arms of these levers are pivoted to a parallel bar 8 which may be of the same width and thickness as the base bar 3 but is preferably somewhat longer than the base bar, the ends of the parallel bar being turned upwardly, as shown at 9, whereby they will avoid contact with the roof. A coiled retractile spring 10 is anchored at one end upon a bolt or stud 11 rising from one of the arms or blocks 4 and at its opposite end is anchored upon a bolt 12 rising from the parallel bar, as

clearly shown. A bolt or other fastening or holding device 13 is secured in one end of the bar 8 and at the opposite end of the bar is an opening 14.

In the particular use of the device illustrated in Fig. 1, a cable 15 is secured at one end about the bolt 13 which is at the lower end of the parallel bar and a ladder 16 is fastened to said cable so that it will be suspended from the anchoring device. In the use of the device, the parallel bar is swung toward the base bar against the tension of the spring 10 so that the levers 6 will be rocked about their fulcrums and their curved ends will be caused to recede from the base bar whereupon the tool may be placed in position upon the roof with the seam or flange between the base bar and the arcuate ends of the levers, as shown in Figs. 1 and 4. The parallel bar is then released and the spring 10 at once contracts so that the levers will be swung in the opposite direction and their arcuate ends caused to grip the flange or seam 2 and bind the same against the base bar. This action is reinforced by the weight of the ladder or platform which is suspended from the lower end of the parallel bar and, of course, acts upon the seam in the same manner that the retractile spring acts thereon. Under some conditions, it may be desirable to place the anchoring device below the support for the workmen in which event the end of the ladder or other support may be fastened firmly to the parallel bar by a bolt or other device inserted through the support and through the opening 14. The weight of the support will then push the parallel bar downward so that the levers will be swung into clamping engagement with the flange of the roof, as before described.

From the foregoing description, taken in connection with the accompanying drawing, it will be seen that we have provided an exceedingly simple and compact tool which may be readily applied to a roof and which will effectually hold a support for the roofer and permit him to proceed with his work without fear of falling.

Having thus described the invention, we claim:

1. An anchoring device comprising a base bar, means for clamping the base bar against a roof seam, means for connecting a workman's support with said clamping means whereby the weight of the support will hold the clamping means in operative position, and means for holding the clamping means in engagement with the roof seam when the weight of the support is removed therefrom.

2. Means for the purpose set forth comprising

100

95

105

110

a base bar adapted to rest against a roofing seam or flange, a parallel bar, means for connecting a roofer's support to the parallel bar, and levers operatively connected with the parallel bar and with the base bar and provided with gripping portions whereby weight imposed upon the parallel bar will cause the gripping portions of the levers to engage the roofing seam and clamp the same against the base bar.

10 3. Means for the purpose set forth comprising a base bar adapted to rest against one side of a roofing seam, arms rigid upon said base bar and

extending laterally therefrom over the roofing seam, levers fulcrumed upon said arms and having arcuate ends adapted to bear against the side of the roofing seam and clamp the same against the base bar, a parallel bar pivoted to the opposite ends of the levers whereby weight applied to said bar will cause the levers to clamp the roof seam, and a retractile spring attached to the parallel bar and to the base bar tending constantly to hold the levers in seam-clamping position.
